UNITED STATES PATENT OFFICE.

SAMUEL J. KELLY, OF WHITE PLAINS, NEW YORK.

COIN-OPERATED DROP-BOX.

976,884.

Specification of Letters Patent. Patented Nov. 29, 1910.

Application filed February 10, 1910. Serial No. 543,051.

To all whom it may concern:

Be it known that I, SAMUEL J. KELLY, a citizen of the United States, residing at 12 Robinson avenue, White Plains, county of 5 Westchester, and State of New York, have invented certain new and useful Improvements in Coin-Operated Drop-Boxes, fully described and represented in the following specification and the accompanying drawings, forming a part of the same.

This invention consists of a particular construction for a package-holder by which the top of the same may be permanently sealed and provided with a lock-chamber, 15 and the package carried and delivered by a package-box movable downward within the casing when unlocked, to deliver the package below the same. Such a package-box is made open upon the front side to remove the package readily therefrom, and it is provided upon the top with means to engage the bolt in the lock, to retain it within the casing until the lock is actuated by suitable means. Such means is shown herein as 20 a coin-slide adapted to receive a coin for retracting the bolt, but no claim is made to such means herein. The casing is formed with a parallel body of rectangular or other prismatic shape, and the package-box is 25 made of similar shape and fitted to slide freely within the casing so as to drop with the package when the bolt is retracted. The back of the casing and of the box are furnished with a slot-and-stud connection or 30 similar means to limit the downward movement of the box.

Figure 1 is a plan of the package-holder; Fig. 2 is a front elevation of the same with the package-box dropped; Fig. 3 is a vertical section of the same at the center line of 40 Fig. 2; and Fig. 4 is a perspective view of the package-box detached from the holder.

A designates the sides of the casing, A' the front, A² the back, and B a panel of glass applied to an opening C in the front A'. The body of the casing is flanged over at the top at a sufficiently to retain a top-plate D in place, which being riveted to the flanges seals the top end of the casing. A 45 plate E is secured within the casing a short distance below the plate D forming a sealed chamber F in which the lock-mechanism is located to operate a bolt b. A hole b' is 50 formed through the plate beneath the locking end of the bolt to receive a lug c' upon the back c of the package-box. Tongues E'

are bent from the plate to hold the glass B in place, and a hooked flange B' is secured within the front of the casing to hold the bottom of the glass in place. The casing is 60 shown of rectangular plan, and the package-box is formed to slide freely within the same, having a back c, a head-piece or top d, a bottom e and sides f, each side having a notch g in its front edge for applying the 65 fingers to the package h, which rests upon the bottom e and which when the box is dropped as shown in Figs. 1 and 2, can be removed from the open front of the box. A slot G of suitable length is formed in the 70 back A² of the casing, and a stud H is secured in the back c of the box to engage such slot, to limit the downward movement of the box when it is unlocked and permitted to drop. 75

In Fig. 3, a portion of the upper part of the box is indicated in dotted lines d' and H' showing the position of the top of the box and the lug c' when it is engaged with the bolt D, and the position of the stud H when 80 the box is pushed up to be locked within the casing. The glass panel and the flange B' which secures it within the casing are both a little narrower than the package-box so that the sides F of the box can slide past 85 the same, and the top D of the box is made a little narrower than the bottom E to clear the glass, as indicated in Fig. 3. The lug c' projects above the top B of the package-box so that when the top is pushed up to the 90 plate E the lug may enter the chamber F and the bolt b enter a slot c² formed in the lug to receive the point of the bolt. The top of the lug and the under side of the bolt are beveled to cause an automatic engagement of the parts when the package-box is pushed up into the casing, the casing being proportioned to wholly inclose the bottom of the package-box when thus locked. To release the box so that it can be dropped to 100 remove the package, a circular coin-opening i is shown in the top-plate D of the casing which connects with a coin-recess in a coin-slide J which is movable by means of a thumb-piece R. The bolt b extends across 105 the chamber F and is shown provided with a stud or roll L against which one edge of the coin K is moved to retract the bolt, when the coin-slide is pushed in by the operator, as indicated in Fig. 1. A detent M is 110 shown to lock the coin-slide when thus pushed in, so as to retain the coin in the

chamber until the detent is unlocked, which is effected by a key N inserted through a key-hole in one side of the chamber.

The mechanism for operating the bolt is wholly immaterial, as the essential feature of the invention is the provision of the bolt and locking mechanism within a sealed chamber in the top of the casing, and a lug or similar means upon the package-box to engage the bolt.

Having thus set forth the nature of the invention what is claimed herein is:

1. A package-holder consisting of a parallel bodied casing having within its top, a bolt and means for actuating the same, a parallel bodied package-box open upon the front and movable downward within the casing to deliver the package below the same, and means upon the package-box for engaging the said bolt.

2. A package-holder having a sealed chamber in the top with a bolt and mechanism therein for shifting the bolt, a rectangular package-box open upon the front and movable downward within the casing to deliver the package below the bottom of the same, a head-piece in the top of the package-box and a lug or hasp projecting upward from the head-piece to engage the bolt.

3. A package-holder having a sealed chamber in the top with a bolt and mechanism therein for shifting the bolt, a rectangular package-box open upon the front and movable downward within the casing to deliver the package below the bottom of the same, a stop to limit the descent of the package-box with the package when unlocked, and means upon the box for engaging the bolt.

4. A package-holder having a sealed chamber in the top with a bolt and mechanism therein for shifting the bolt, a rectangular package-box open upon the front and movable downward within the casing to deliver the package below the bottom of the same, the back of the casing and the back of the package-box having a slot and stud engagement to limit the descent of the box, a head-piece in the top of the box and a lug or hasp projecting above the head-piece to engage the bolt.

5. A package-holder having a sealed chamber in the top with a bolt and mechanism therein for shifting the bolt, a rectangular package-box open upon the front and movable downward within the casing to deliver the package below the bottom of the same, the sides of the package-box being notched at their front edges for grasping the package, and means upon the package-box to engage the bolt.

6. A package-holder consisting of a rectangular casing, with a bolt and means for actuating the same in the top of the casing, the casing having an opening upon the front with a glass panel secured therein, a rectangular package-box open upon the front to expose such package behind such panel and movable downward within the casing to deliver the package below the same, and means upon the package-box to engage the bolt.

7. A package-holder consisting of a rectangular casing, with a bolt and means for actuating the same in the top of the casing, the casing having an opening upon the front with a glass panel of less width than the casing, a rectangular package-box having back, top and bottom, and sides movable within the casing at the edges of the panel, and means projected above the top of the package-box to engage the bolt.

8. A package-holder having a sealed cover at the top, a partition below the same forming a lock-chamber with a hasp-hole in such partition, a bolt movable in the chamber across the hasp-hole, mechanism within the chamber for shifting the bolt, a package-box having top and bottom and open front and movable downward within the casing to deliver the package below the same, and a lug or hasp projected from the package-box above its top and adapted to enter the hole in the partition and engage the bolt.

In testimony whereof I have hereunto set my hand in the presence of two subscribing witnesses.

SAMUEL J. KELLY.
